UNITED STATES PATENT OFFICE

WILLIAM MESSERSCHMIDT, OF NEW YORK, N. Y., ASSIGNOR TO RICHFIELD OIL CORPORATION, OF NEW YORK, N. Y.

DESIGN FOR A SIGN

Application filed December 14, 1931. Serial No. 42,070. Term of patent 14 years.

To all whom it may concern.

Be it known that I, WILLIAM MESSERSCHMIDT, a citizen of the United States, residing at New York, in the county of New York and State of New York, have invented a new, original, and ornamental Design for a Sign, of which the following is a specification, reference being had to the accompanying drawings, forming a part thereof.

Figure 1 is a side elevational view of a sign, showing my new design;

Figure 2 is a bottom plan view of the same.

I claim:

The ornamental design for a sign, as shown.

WILLIAM MESSERSCHMIDT,
